UNITED STATES PATENT OFFICE.

CHARLES H. EGGLESTON, OF MARSHALL, ASSIGNOR OF ONE HALF TO
EDWARD O. ELY, OF GRAND RAPIDS, MICHIGAN.

BUTTON-SETTING INSTRUMENT.

SPECIFICATION forming part of Letters Patent No. 293,234, dated February 12, 1884.

Application filed November 9, 1883. (No model.)

To all whom it may concern:

Be it known that I, CHARLES H. EGGLESTON, a citizen of the United States, residing at the city of Marshall, in the county of Calhoun 5 and State of Michigan, have invented a new and useful Setting-Instrument for Attaching Buttons to Leather and other Fabrics, of which the following is a specification.

The invention relates to that class of setting 10 devices used in clinching metallic staples or fasteners which engage with the eye of the button and have prongs which pass through the fabric and are clinched on the side of the fabric opposite the button; and the object of 15 my invention is to produce a setting device which can be used conveniently for setting and clinching an ordinary metallic staple, and have the two prongs of the staple, if desired, in a line at right angles with the strain on the 20 button. This object I accomplish by means of the mechanism illustrated in the accompanying drawings, in which—

Figure 1 is a side elevation of my setting device in perspective. Fig. 2 is likewise a side 25 elevation, but with a portion of the jaws cut away in order to show the position of the metallic staple and button in the jaws. Fig. 3 shows the form of the metallic staple after the button has been attached to the fabric. Fig. 30 4 shows a perspective view of the front end of the setting device; and Fig. 5, a perspective view of the guide detached, showing the form of the groove and slot used for holding the staple and button.

Similar letters refer to similar parts throughout the several views.

In the drawings, J and J' represent the jaws of the setting device, and C C the handles. One jaw and one handle may be in one piece, 40 and the jaw may be attached by a bolt or rivet, in the manner of ordinary nippers.

G is a guide placed between the jaws, and may be attached by the same rivet which attaches the jaws, and may be so attached as to 45 be moved to or from either jaw. The guide G is provided with a groove, t, for the reception of the staple S, and a slot, i, for the reception of that portion of the button-eye which is between the staple and the button. n is a 50 groove for the reception of that portion of the button-eye that is below the staple. This con-

struction allows the operator to place the staple in the groove t, and the button, being at the outer end of the guide G, is entirely out of the way of the jaws.

e is the fabric in position to receive the staple S, and B is the button.

The jaw J is flattened and provided with two or more grooves for directing the points of the staples after they have been pressed 60 through the fabric against the jaw. The jaw J' has a projection, so constructed that when the jaws are brought toward each other the projection passes into the groove t of guide G. This projection is provided with a recess or 65 slot, P, leaving two projections, one on either side of slot P, and they are each grooved so as to fit upon the back of the staple. When a flat or rectangular piece of metal is used for the staple, the grooved form may be dispensed 70 with. The object of the slot P is to receive the eye of the button and to allow the projecting ends of the jaw to press directly on the staple.

The operation of my invention is as follows: 75 The staple is placed in the eye of the button and the staple then placed in the groove t in the guide G, the points of the staple being toward the jaw J, and the rounded portion toward J'. The slot i receives the upper part of 80 the button-eye and allows it to be moved freely therein. The fabric is placed between the jaw J and the guide G, the position of the fabric, the staple, and the button being shown in Fig. 2. Now, by closing the jaws the staple 85 is driven through the fabric, and coming in contact with the grooved face C of jaw J, the points are turned toward each other and clinched, thereby attaching the button to the fabric. By means of my device the staple 90 may be driven through the fabric, so that the two prongs pierce it in a line at right angles with the strain upon the staple, so that when the button is attached to any article the strain on the button will produce an equal strain on 95 each prong of the staple, which makes a very strong and durable attachment. By the use of a single or two pronged staple the button can readily be detached by cutting the staple, and the fabric is not cut or torn by the use of 100 such a staple.

In the drawings I have shown a setting de-

vice designed to be used by hand and for attaching one button at a time; but the setting device may be constructed to be operated by any suitable power, and instead of being constructed to set one button at a time, it may be so made as to hold and attach any number of buttons at one movement of the jaws.

Having thus described my invention, what I claim to have invented, and desire to secure by Letters Patent, is—

In a button-setting instrument, the guide G,

provided with the slot *i*, and groove *t*, placed between and in combination with the jaws J and J', the groove *t* and the slot *i* being so placed with reference to each other that the groove *t* will receive the staple and the slot *i* the eye of the button, substantially as described.

CHARLES H. EGGLESTON.
